FRONT FENDER CONSTRUCTION

Edmund E. Anderson, Pleasant Ridge, Mich., assignor to General Motors Corporation, Detroit, Mich., a corporation of Delaware

Application September 23, 1939, Serial No. 296,191

8 Claims. (Cl. 180—69)

This invention relates to the front end metal construction of automotive vehicles.

The improvement relates to novelties in the details of construction and the manner of making and assembling the front fenders and the intermediary grille work, and in the arrangement of these parts.

The fender itself has the novelty of being formed in three parts: (1) the main fender part, comprising the top of the fender and the permanent side of the hood; (2) a filler piece extending between the tip of the fender and the hood; and (3) a front tip piece complementary to and completing the front of the main part of the fender. The main part of the fender and the filler piece have complementary half lamp housings formed therein which when in assembled relation form the complete housing for the headlamps.

On the drawings

Figure 1 is a perspective view of the front end of an automotive vehicle showing the invention applied.

Figure 2 is a front elevational view of the fender removed from the vehicle and showing some adjacent parts in dotted outline.

Figure 3 is a plan view of the fender of Figure 2.

Figure 4 is a side elevation of the fender of Figure 2.

Figures 5, 8, 15, and 16 are sectional views on corresponding lines of Figure 2.

Figures 6 and 7 are sectional views on the corresponding lines of Figure 3.

Figures 9 and 10 are sectional views on the corresponding lines of Figure 4.

Figure 11 is a side view of the front end of the vehicle but with the fender removed and showing the manner of mounting the parts on the vehicle frame.

Figures 12, 13, 14, 17 and 18 are sections on the corresponding lines of Figure 11.

Referring to the drawings, the numeral 2 indicates a vehicle as a whole. The vehicle has the top 4, the V-shaped windshield 6, the front door 8, front door window 10, cowl 12, radiator 13, running board 14, and front wheels 16 suitably mounted on a chassis or frame 18 (Figure 11). These parts are conventional, and per se form no part of the invention.

The hood 20 of the vehicle extends forwardly of the cowl 12 and has the door 22 which is hinged at its rear end and adapted to open from the front end. Each side of the vehicle has a front fender 24 and between the two fenders there is posi-

tioned the perforate grille 26 which allows the entrance of air to the usual radiator. A dummy or ornamental grille 28 is positioned at each side of the vehicle, and the ornamental grille 28 and the perforate grille 26 are connected by a curved panel 30.

Referring to Figures 2-10 inclusive, each fender 24 comprises the main fender part 32, the filler piece 34 and the tip piece 36. The main part 32 extends from the forwardmost part of the vehicle rearwardly to substantially the front edge of the front door 8 as is best shown in Figure 1. This part 32 has the integral wing 38 which forms a stationary part of the hood side. A curved part 40 conforms to the shape of the wheel 16 and allows the wheel to be turned. The fender has an inturned flange 41 at the curve 40. To the rear of the curved part 40 the fender turns inwardly as indicated at 42 and the lower edge 44 of part 42 is rigidly secured to the running board 14. The front end of the main part 32 has formed therein the half round housing 46 which is pressed from the metal of part 32 when it is formed in the press. This lamp housing half 46 projects upwardly from the fender part and extends from the tip of the fender rearwardly for a distance sufficiently to house the lamp and to cause the end of the housing gradually to fade into the fender.

The filler piece 34 has a part 48 which forms a part of the hood side. A half lamp housing 50 is formed in the filler piece 34. This half lamp housing 50 is complementary to the half lamp housing 46 in the main fender part 42. When the parts are in position, the two half housings 46 and 50 mate and together form a lamp housing 52 for the headlamp of the vehicle. The dividing line between the filler piece 34 and the main fender part 32 is shown at 54 and this dividing line is welded as is best shown in Figure 6. After the weld has been completed the joint formed at the line 54 is smoothed down so that in the final appearance the weld line is not distinguishable.

At the top of the lamp housing 52, parts 50 and 46 overlap as is shown at 56 and these overlapping parts are secured together by the spot welds 58, Fig. 7. The overlapping of the parts at 56 forms a place for the positioning of a suitable ornament.

At the front lower part of the housing 50 parts 32 and 34 are united as is best shown in Figure 8. The adjacent edges overlap and are spot welded as indicated at 60.

The tip piece 36 is formed separately and in the final assembly is a continuation of the front end 55.

of the main fender part 32. The front face of the tip piece 36 is rounded in front as indicated at 62 and the side edge at the wheel housing is formed on a curve as indicated at 64. This curve 5 64 is a continuation of the curve 40 and conforms generally to the curvature of the tire on wheel 16. As is best shown in Figures 9 and 10, the curved edge 64 of the tip piece 36 is return bent as indicated at 66 to give it strength and where 10 the curve 64 merges into the curve 40 the edge is flattened as indicated at 68. The meeting line 70 between parts 32 and 36 is formed by the in-turned flanges 72 on the main fender part 32, and the flange 74 on the tip piece 36. These two parts 15 are then united at the flanges by means of spot welds 76.

As is best shown in Figure 4, there is a slight projection 78 at the front of the main fender part 32 and this projection extends slightly beyond 20 the tip piece 36. The purpose of this is ornamental.

Figure 5 shows the manner in which the ornamental or dummy grille 28 is secured to the fender part 36 and to the main grille 26. The fender tip 25 36 has the in-turned flange 80 which mates with a flange 82 on the edge of the ornamental grille 28. A strip of anti-squeak material 84 is positioned between the two flanges and U-shaped nuts 86 are slipped over the flange 82 and the openings 30 in the nuts conform to the openings 88 in the flange 82. A strengthening strip 90 is positioned over the flange 80 and a bolt 92, provided with a washer 94, passes through openings in the reinforcing strip 90, the flange 80, the anti-squeak 35 material 84, the flange of the nut 86, and the opening 88 in the flange 82, and is screw threaded into the threaded part 96 of the nut 86. This structure will rigidly hold the fender part 24 and the dummy grille 28 together. The grille 26 is 40 provided with an edge flange 98 and nuts 86 are slipped over this flange and bolts 94 are then passed through the flanges 82 on the dummy grille, through an opening in the plate 100, through the opening in the flange 98, and screw 45 threaded into the threaded part 96 of the nut 86. This structure will securely hold the dummy grille and the grille together.

Figures 11-18 inclusive show the manner of mounting the front end construction on the 50 chassis 18.

The chassis has a cross member 102 which extends from one side bar to the other and the cross member is generally U-shaped in cross section. The cross member has mounted at the 55 middle point thereof a U-shaped brace or harness 104. This harness 104 is mounted at the mid part of its bottom in the manner shown and described in the patent to Waterbury 2,004,258. The upright arms of the U extend substantially 60 to the line at 106 where the hood door 22 joins the side 38 of the hood. Two plates 108, one on each side of the vehicle, are secured at their forward edges by means of the fastening elements 65 110 to the upright member of the U-frame 104, and at the rear end these plates are made to overlap and are secured to the cowl as indicated at 112. The upper edges of the plate 108 are outwardly flanged as indicated at 114 in Figure 70 13, and the upper edge of the hood side part 38 is likewise inwardly flanged as indicated at 116. Nuts 118 are slipped over the flange 114, and bolts 120 passing through suitable openings in flanges 114, 116 are screw threaded into the nuts 75 118 and hold the flanges 114 and 116 rigidly to-

gether. The hood door 22 has an inturned flange 122 which rests on the flange 116 of the hood member 38.

The upper end of the U-shaped brace 104 is outturned as indicated at 124 in Fig. 12, and an angle iron 126 is positioned at the angle formed at the top of the U brace. The flange 116 overlaps the outwardly turned end 124 and a reinforcing strip 128 is positioned between the flange 116 and the outturned end 124. The nut 130 is positioned over the flange 124 and the angle iron 126, and a bolt 132 passes through parts 116, 128, 124, and 126 and is screw threaded into the nut and rigidly holds the parts together.

At the rear lower part of the plates 108 a second 15 smaller plate 134 is positioned to fill in the corner caused by the downwardly bent part of the frame 18. This plate 134 is secured at its upper edge to the plate 108 and at its lower edge is provided with flanges 136 which are secured to the frame. 20

Figure 14 shows the manner in which the fender is secured to the running board and automobile body at its rear end. A part of the body is indicated at 138 while the rear part of the fender is indicated at 32. The numeral 140 indicates a reinforcement to strengthen the parts. The running board 14 has a piece of rubber 142 positioned between the running board and the end of the fender 32 to form a seal to prevent the entrance of water and also to form a more rigid 30 securing means for the end of the fender. This securing bracket 144 has one end 146 secured by means of the bolt 148 to the automobile body 138 and its other end 150 secured by means of the bolt and nut 152 to the bottom part of the fender 35 32 and to the running board 14.

As is seen in Figure 14, the bottom part of the fender 32 has the inturned reinforcing flange 154.

Figure 15 shows the connection between the grille 26 and the filler piece 34. The filler piece 40 has the inturned flange 156 at its bottom side while the grille has a flange 158 at its upper edge. The two flanges overlap and are secured together by means of the bolt and nut 160.

Figure 16 shows the connection between the 45 filler piece 34 and the decorative or dummy grille 28. The dummy grille has the flange 162 at its upper edge and over the flange there is passed the U-shaped nut 164. Anti-squeak material 168 is placed between flanges 162 and 156 and a bolt 170 is threaded into the nut 164 and holds the parts together.

Referring to Figure 17, there is shown the connection between the chassis and the bottom part of the fender and running board. The running 55 board has the downturned flange 172 which is secured to the lower edge of the fender part 32 by means of the bolt and nut 174. The inturned flange 176 of the fender has the outer end of a securing strip 176 secured thereto by means of the bolt and nut 178 while the inner end of the strip 176 is secured by means of the bolt 180 to the frame 18.

In Figure 18 the manner of securing the fender 65 to the cowl is shown. The fender part 32 has the inturned flange 182 (see Figures 2 and 18) and a reinforcing member 184 thereover. The cowl is indicated at 12 and inside the cowl a reinforcing plate or strip 186 is applied. Suitable anti-squeak 70 material 188 is used between the flange 182 and the cowl 12. These parts are secured together by means of bolt 190 which passes through suitable mating openings and is screw threaded into a nut 192 retained by the end of the reinforcement 184. 75

A flange 193 (Figure 2) at the rearmost part of the fender is used to secure the fender to the body.

5 At the front part of the vehicle there are positioned the two air directing plates 100. One plate is at each side of the vehicle. The manner in which the plates are secured at their front edges is shown in Figure 5. Their rear edges 194 terminate substantially where they meet the front 10 rear edges of the plates 108, and these plates extend from the frame 18 upward to the underside of the filler piece 34 and the upper edge of the plate is shaped to correspond to the shape of the underside of the filler piece. The function 15 of these plates is to direct the air which passes through the grille 26 into the usual radiator core. At their rear edges 194 the plates 100 are secured to the upright arm of the U-shaped brace 104.

I claim:

20 1. In a hood and front end construction for a motor vehicle, two fenders, one fender at each side of the vehicle, each fender including a plurality of pieces rigidly secured together, said pieces comprising a main piece extending from the tip of the fender to substantially the edge of the front door of the vehicle, a tip part extending from the front end of the main part downwardly in front of the front wheel, and a filler part extending from the hood side outwardly and terminating in a lamp housing section, said main fender part having a lamp housing section complementary to the lamp section in the filler part, said two sections forming a lamp housing.

25 2. In a hood and front end construction for a motor vehicle, two fenders, one fender at each side of the vehicle, each fender including a plurality of pieces rigidly secured together, said pieces comprising a main piece extending from the tip of the fender to substantially the edge of the front door of the vehicle, a tip part extending from the front end of the main part downwardly in front of the front wheel, and a filler part extending from the hood side outwardly and terminating in a lamp housing section, said lamp section extending above and out of the plane of the fender, said main fender part having a lamp housing section extending out of the plant of the fender and complementary to the lamp section in the filler part, said two sections forming a lamp housing.

30 3. In a hood and front end construction for a motor vehicle, two fenders, one fender at each side of the vehicle, each fender including a plurality of pieces rigidly secured together, said pieces comprising a main piece extending from the tip of the fender to substantially the edge of the front door of the vehicle, a tip part extending from the front end of the main part downwardly in front of the front wheel, a filler part extending from the hood side outwardly and terminating in a lamp housing section, said main fender part having a lamp housing section complementary to the lamp section in the filler part, said two sections forming a lamp housing.

35 4. In a hood and front end construction for a motor vehicle, two fenders, one fender at each side of the vehicle, each fender extending over a front wheel, said fenders forming the side of the hood, a connection between the fenders comprising two dummy grilles secured to the fenders, an air passage grille interconnecting the dummy

grilles, and a bottom panel piece extending across the front of the vehicle and secured to the dummy grilles and the air grille.

5. In a hood and front end construction for a motor vehicle, two fenders, one fender at each side of the vehicle, each fender comprising a main part extending over the front wheel and rearwardly to substantially the front door and forming the hood side and having an arched cut-out to enable the turning of the front wheel, a front tip part extending from the main part downwardly in front of the front wheel and joined to the main part in a plane substantially tangent with the top of the arched cut-out, and a filler piece extending from the main part to the hood side at the forwardmost part of the main part.

6. In a hood and front end construction for a motor vehicle, two fenders, one fender at each side of the vehicle, each fender comprising a main part extending over the front wheel and rearwardly to substantially the front door and forming the hood side and having an arched cut-out to enable the turning of the front wheel, a front tip part extending from the main part downwardly in front of the front wheel and joined to the main part in a plane substantially tangent with the top of the arched cut-out, and a filler piece extending from the main part to the hood side at the forwardmost part of the main part, said main part and said filler part each having a half section of a lamp housing formed therein, said sections being complementary to form the lamp housing.

7. In a hood and front end construction for a motor vehicle, two fenders, one fender on each side of the vehicle, each fender including three parts, comprising a main fender part extending from the extreme front end of the vehicle to substantially the edge of the front door and forming a stationary part of the hood side and having a curved cut-out part conforming to the curvature of the rear of the front wheels, said main part having a half headlamp housing formed therein, a filler piece having formed therein a half headlamp housing mating with the half housing of the main part and forming therewith a headlamp housing, said filler piece extending from the main part at the extreme front end thereof to the hood side and having a part forming a portion of the hood side, and a tip piece secured to the front end of the main part and forming a continuation thereof, said tip piece extending downwardly in front of the front wheel, and a dummy grille member secured to the main part, the filler piece, and the tip part and forming a continuation of the main part and the tip piece.

8. In a hood and front end construction for a motor vehicle, two fenders, one fender on each side of the vehicle, each fender including three parts, comprising a main fender part extending from the extreme front end of the vehicle to substantially the edge of the front door and forming a stationary part of the hood side and having a curved cut-out part conforming to the curvature of the rear of the front wheels, said main part having a half headlamp housing formed therein, a filler piece having formed therein a half headlamp housing mating with the half housing of the main part and forming therewith a headlamp housing, said filler piece extending from the main part at the extreme front end thereof to the hood side and having a part forming a portion of the hood side, a tip piece secured to the front end of the main part and forming a

continuation thereof, said tip piece extending downwardly in front of the front wheel, a dummy grille member secured to the main part, the filler piece, and the tip part and forming a continuation of the main part and the tip piece, an air grille extending across the front of the vehicle

and secured to the dummy grilles and filler pieces, and a panel extending between the dummy grilles and secured to the dummy grilles and the main grille.

EDMUND E. ANDERSON. 5
